(12) **United States Design Patent** (10) Patent No.: **US D935,771 S**
(45) Date of Patent: **** Nov. 16, 2021**

(54) **TOOL BOX**

(71) Applicants: **Keter Plastic Ltd.**, Herzliya (IL);
Milwaukee Electric Tool Corporation,
Brookfield, WI (US)

(72) Inventors: **Yaron Brunner**, Kibbutz Gvat (IL);
Omer Menashri, Kibbutz Afikim (IL);
Izhar Shani, Kibbutz Gvat (IL); **Uri**
Parizer, Kibbutz Hukok (IL); **Grant T.**
Squiers, Cudahy, WI (US)

(73) Assignees: **Keter Plastic Ltd.**, Herzliya (IL);
Milwaukee Electric Tool Corporation,
Brookfield, WI (US)

(**) Term: **15 Years**

(21) Appl. No.: **29/703,805**

(22) Filed: **Aug. 29, 2019**
